JOSEPH WATSON, OF BUFFALO, NEW YORK, ASSIGNOR TO HIMSELF AND
SOLOMON DRULLARD, JR., OF SAME PLACE.

Letters Patent No. 71,433, dated November 26, 1867.

IMPROVEMENT IN CONSTRUCTING FURNACE-DOORS.

The Schedule referred to in these Letters Patent and making part of the same.

TO ALL WHOM IT MAY CONCERN:

Be it known that I, JOSEPH WATSON, of the city of Buffalo, in the county of Erie, and State of New York, have invented certain new and useful Improvements in the Construction of Furnaces; and I do hereby declare that the following is a full and exact description thereof, reference being had to the accompanying drawings, making part of this specification, in which—

Figure 1 is a front elevation of a furnace provided with my improvement.

Figure 2 is a vertical cross-section through the door and arch in plane of line $x\ x$, fig. 1.

Figure 3 is a front elevation of the brick or piece forming the door-arch.

Figure 4 is a horizontal section of the door in the plane of line $y\ y$, fig. 1.

Like letters of reference designate corresponding parts in all the figures.

My invention consists in the peculiar manner of constructing the door and arch of puddling and heating-furnaces, each being formed of a single piece or brick, and an iron frame, substantially as hereinafter described.

In the drawings, A represents the brick, and B the iron frame, which together form the door; C, the brick arch-piece, and D the iron frame or cross-plate of the same; E E, the jambs, and F a portion of the roof of the furnace.

The brick for the door is first moulded of the full size of the recess in which the door fits, the outer edges and sides being recessed, so that the rectangular iron frame B may be cast therein. This frame is made of a size a little less than that of the inner face of the door, as represented, and is provided with two cross-pieces of plates, $g\ g$, of wrought iron, which fit in corresponding recesses formed for their reception. The brick portion being moulded of the required form, as above stated, it is then placed in a mould, the malleable bars g arranged in their recesses, when the frame is cast around it, sockets having previously been formed in the brick at each edge to receive the lugs h , which are cast with the frame, and by which the frame is firmly secured to the brick, as represented in figs. 1 and 4. I is a link, at the centre and top of the frame, by which the door is raised by a lever in the usual manner. By this mode of constructing the door, the iron frame is wholly protected from the direct heat of the furnace, and consequently will last much longer than when constructed in the ordinary manner.

Where the door is made in the usual manner, of small brick, surrounded by an iron frame, the lower edge of the latter, being subject to the intense heat of the furnace, soon burns away, and the bricks fall down, when a new door has to be constructed, involving the loss of material and time of the hands remaining idle, in addition to the cost of the door. By my mode of construction, the greater part of this expense is avoided. If the lower portion of the frame should in time burn away, the door, being of an entire brick, would be still sustained by the cross-bars g and lugs h , which would be inadequate for the purpose if the door were formed of small and separate brick, in the common manner. The door-arch is also constructed of one entire piece, C, of the form shown, a recess being made for the iron cross-plate or frame D, which is of the ordinary construction.

The inner side of the arch-piece is made inclined, as shown at l , in fig. 2, so as to form a key and support for the roof F, while the frame D sustains the arch against the horizontal pressure towards the front.

When the arch is formed of small brick, in the common way, the flame works in the joints, melting portions of the brick, that run down, forming pendants, obstructing the aperture of the door, which, in filling the furnace, are liable to be struck and broken off, and not unfrequently resulting in the falling down of the entire arch. The expansion and contraction of the arch also has a tendency to loosen the brick, and hasten the destruction of both door and arch, when of this construction. My improvement prevents, in a great measure, all of these difficulties.

In common door-frames the entire back is of iron, which requires twice the amount of metal that mine does; besides, they confine the outer surface of the brick from the external air, which in mine has free access thereto, keeping it comparatively cool. Forming the arch of a single brick not only makes the same much more durable, and supports the roof better, but also enables the recess for the iron frame to be readily moulded in the brick, and thereby saves the labor of cutting and fitting the brick in the ordinary manner, while the joint between the two is more perfect. In the common method, the displacement of a single brick by the expansion of the arch

under the intense heat will often force the door off, so as to leave a crevice, through which the flame escapes; but when the crown-piece is entire such a result cannot possibly occur, the expansion being general and equal.

What I claim as my invention, and desire to secure by Letters Patent, is—

1. Constructing furnace-doors of a single brick, A, in combination with an iron frame, B, substantially in the manner and for the purpose set forth.

2. I also claim the manner of constructing the frame B, with the wrought-iron cross-bars *g g*, and lugs *h h*, for sustaining the brick and securing them in the frame, substantially as specified.

3. I also claim constructing the door-arch of a single crown-piece, C, formed with an inclined back, *l*, and recess in front, for and in combination with the iron plate D, substantially as and for the purpose set forth.

In witness whereof I have hereunto signed my name in the presence of two subscribing witnesses.

JOSEPH WATSON.
